UNITED STATES PATENT OFFICE.

THOMAS C. WHITEHEAD, OF DETROIT, MICHIGAN

LUBRICATING SYSTEM.

Application filed August 25, 1924. Serial No. 734,081.

This invention relates generally to lubricating systems and consists of certain novel features of construction, combinations and arrangements of parts as will be more fully described and particularly pointed out in the appended claims.

In the accompanying drawing:

Figure 1 is a front elevation of a pump casting embodying my invention;

10 Figure 2 is a top plan view thereof;

Figure 3 is a vertical sectional view taken on the line 3—3 of Figure 2;

Figure 4 is a detail elevation of the bearing plate which is attached to the crank case.

15 Referring now to the drawing in which like characters of reference designate corresponding parts throughout the several views, the numeral 1 designates a pump casing that is preferably formed of an integral cylinder 2 and a crank case 3. As shown, the crank case 3 is preferably provided at its lower end with a removable pan 4 and has a detachable plate 5 at one side thereof through which a suitable crank shaft 6 extends. This shaft 20 also extends through a vertical partition or baffle 7 projecting downwardly from the lower end of the cylinder 2 and is journaled in suitable bearings 8 and 9 respectively extending through the plate 5 and partition 7.

30 In order that a suitable lubricant such as oil, in the crank case may be supplied to the bearings 8 and 9 and also to the outer surface of the crank pin 10 upon which the lower end of the connecting rod 11 is mounted, I prefer-

35 ably provide a suitable fly wheel 12 that is non-rotatably secured to the reduced inner end portion 13 of the crank shaft 6 and is provided upon opposite sides thereof with suitable radially extending grooves or recesses 14 for picking up oil from the crank case and throwing it into a downwardly inclined trough 15 leading to a receptacle or pocket 16 at one side of the crank case. For conveying the oil from the receptacle to the 40 bearings and crank pin I preferably provide a short tube 17 that communicates with a longitudinally extending bore 18 and the branch transversely extending bores 19 in the crank shaft 6. As shown, the tube 17 is prefer-

50 ably journalled in a suitable bearing 20 extending through the inner wall 21 of the receptacle and threadedly engages the walls of a longitudinally extending socket 22 in the inner end of the crank shaft 6. The short branch bores 19 in the crank shaft are preferably spaced the proper distance apart so that

they will lead to the bearings 8 and 9 and to the connecting rod 11. Thus, the arrangement is such that when the crank shaft 6 is rotating rapidly, centrifugal action will 60 throw outward any lubricant collecting in the branch passages or bores 19. This will produce suction which will be communicated through the longitudinally extending bore 18 and the tube 17 to the receptacle 16, consequently the lubricant will be withdrawn steadily from the receptacle, while the crank shaft is rotating for the proper lubrication of the bearings. Inasmuch as the partition 7 extends downwardly through the lower end 70 of the cylinder 2 and terminates short of the pan 4 at the bottom of the crank case, it is readily apparent that the lubricant in the chamber 23 containing the crank 24 and connecting rod 11 may be returned readily to the 75 chamber 25 containing the fly wheel 12 and that the lubricant thrown upwardly and outwardly by the fly wheel will be confined to the chamber 25. Thus, the centrifugally thrown lubricant will be directed toward the trough 80 15 or receptacle 16.

While it is believed that from the foregoing description the nature and advantages of the invention will be readily apparent, I desire to have it understood that I do not limit 85 myself to what is herein shown and described, and that such changes may be resorted to when desired as fall within the scope of what is claimed.

What I claim as my invention is:

1. The combination with a crank case containing lubricant, of a rotatable crank shaft in said case having a longitudinally extending bore, a receptacle in the case, centrifugal means for transferring lubricant from the 90 crank case to the receptacle, bearings for the crank shaft, and a tube positioned within said shaft and communicating with the longitudinally extending passage therein for conveying lubricant from the receptacle to the longitudinally extending bore in the shaft, said shaft having means for supplying lubricant from said longitudinally extending bore to 95 said bearings.

2. The combination with a crank case containing lubricant, of a rotatable crank shaft in said case having a longitudinally extending bore, a receptacle in the case, means for transferring lubricant from the crank case to the receptacle, bearings for the crank shaft, 110 and a separate tube arranged within said shaft and communicating at one end with the recep-

tacle and at the opposite end with the longitudinally extending bore in the shaft for conveying lubricant from the receptacle to the longitudinally extending bore in the shaft, 5 said shaft having transversely extending passages for supplying lubricant from said longitudinally extending passage to said bearings.

3. The combination with a crank case containing lubricant, of a partition in the case 10 terminating short of the bottom thereof, of a crank shaft extending through the partition and a wall of the crank case, said shaft having a longitudinally extending bore, a receptacle in the crank case in communication with 15 the longitudinally extending bore in the shaft and adapted to contain a supply of lubricant, means for transferring the lubricant from the crank case to the receptacle, and bearings for said crank shaft, said shaft having means for 20 supplying lubricant from said longitudinally extending bore to said bearings.

4. The combination with a crank case containing lubricant, of a partition in the case terminating short of the bottom thereof, a 25 crank shaft extending through the partition and a wall of the crank case, said crank shaft having a longitudinally extending bore, a receptacle in the crank case in communication with the longitudinally extending bore in the 30 shaft and adapted to contain a supply of lubricant, a fly wheel mounted on the crank shaft between the partition and the receptacle having means for transferring lubricant from the crank case to the receptacle, and bearings 35 for the crank shaft, said shaft having pas-

sages for conveying lubricant from the longitudinally extending bore to the said bearings.

5. The combination with a crank case containing lubricant, and a rotatable crank shaft in said case, of a receptacle in the crank case, 40 means for transferring lubricant from the crank case to the receptacle, bearings for the crank shaft, a tube journaled in a wall of the receptacle and detachably connected to the shaft for conveying lubricant from the receptacle to the longitudinally extending bore in the shaft, said shaft having means for conveying lubricant from said longitudinally extending bore to said bearings. 45

6. The combination with a crank case containing lubricant, of a partition in the crank case terminating short of the bottom thereof, a crank shaft extending through said partition and a wall of said crank case, and having a crank portion disposed between said partition and the adjacent wall of the crank case, a receptacle in the crank case upon the opposite side of the partition, a fly wheel non-rotatably mounted on the crank shaft between the partition and the receptacle having means 50 for transferring lubricant from the crank case to the receptacle, bearings for the crank shaft engaging the partition and wall aforesaid of the crank case, a connecting rod mounted on the crank portion of the shaft, and means for conveying lubricant from the receptacle through the fly wheel and shaft to the bearings and connecting rod. 55

In testimony whereof I affix my signature.
THOMAS C. WHITEHEAD.
